UNITED STATES PATENT OFFICE.

JOSEPH MIDGLEY, OF WASHINGTON, RHODE ISLAND, ASSIGNOR OF ONE-HALF TO
WILLIAM BOWKER, OF WASHINGTON, RHODE ISLAND.

BUNCH-PREVENTER.

1,121,524.

Specification of Letters Patent. Patented Dec. 15, 1914.

Application filed November 22, 1913. Serial No. 802,415.

To all whom it may concern:

Be it known that I, JOSEPH MIDGLEY, a subject of the King of Great Britain, residing at Washington, in the county of Kent and State of Rhode Island, have invented 5 certain new and useful Improvements in Bunch-Preventers, of which the following is a specification, reference being had therein to the accompanying drawing.

10 In combing and other similar machines now generally in use, trouble is experienced from the collection, in bunches or other form, of dust or short-staple fiber, from the material being treated, under the bearings of the rolls, in the spaces between the bearings, and on the rolls between the ends of the leather or other fabric covering and the journals. Accumulations of this kind 15 increase the resistance of the rolls to rotation, and from time to time they are drawn into the good material passing from the machine and become incorporated with the material in such manner that it is impracticable to remove it, with the result that uneven 20 25 yarns are produced and the value of the output otherwise lessened.

The device provided by this invention is applicable to machines of the kind indicated now in use, and it operates to prevent 30 the fouling of roll-bearings and the assimilation of fouling matter by material passing through a machine with which it is associated.

When read in connection with the description herein, the details of the invention and 35 its manner of use will be apparent from the accompanying drawing, forming part hereof, wherein an embodiment of the invention as applicable to a combing-machine is 40 closed, for purposes of illustration.

While the invention is exemplified herein in a preferable form, it is to be understood that it is not the intention to be limited necessarily thereto in interpretation of the 45 claims, as changes within the scope of the claims can be made without departing from the nature and spirit of the invention.

Like reference-characters refer to corresponding parts in the views of the drawing, 50 of which—

Figure 1 is a side view of the device; Fig. 2 is a perspective view, looking at the other side; Fig. 3 is an end view; Fig. 4 is a view

of the device on a roll; Fig. 5 is a perspective view of a portion of a combing-machine 55 showing the device in place; and Fig. 6 is a sectional view, on the line 6—6, Fig. 5.

Having more particular reference to the drawing, 7 designates the device provided by the invention. In the form shown, the 60 device is made of strong sheet metal, of a suitable width to contact with certain parts, and bent or otherwise fabricated to present 65 reversely-curved faces or surfaces adapted to lie against or cover those parts. The intermediate portion constitutes a holding and protecting part 8, shaped to conform to and partially embrace a roll near its end beyond the part that is fluted or covered with 70 leather or other fabric. Continuing from 70 the intermediate part in a reverse curve is an end portion 9, shaped to conform to and lie against an adjacent roll. The end portion 9 is extended to one side, whereby it is 75 wider than the intermediate portion. A covering 10, of leather or other suitable fabric, is secured to both sides of portion 9. This covering extends on the convex side to or about to the concave side of the holding 80 part 8, and it extends from the concave side 85 of portion 9 over a part of the convex side of the holding part. The covering also extends above the part of the wider portion 9 that projects laterally beyond the holding part, and here the two flaps of the covering 85 material are secured together, by cement or other means, whereby a single flap 11 is formed. The material of the device, in the end portion opposite to portion 9, is bent or otherwise disposed to form a part 12 extending 90 in a diverse direction from portion 9, for the purpose of having the end of a weight or spring stirrup seat thereagainst and to contribute to retention of the stirrup in place.

A manner of associating the device with 95 rolls is illustrated by several figures of the drawing, and particularly by Figs. 5 and 6, which show parts of a combing-machine having adjacent coöperating rolls.

Referring particularly to Figs. 5 and 6, 100 the machine has a lower piecing-roll 13, which ordinarily is fluted and usually is formed on a longitudinal shaft common to all combing-heads and driven from the drive-head of the machine at one end; an upper 105 fluted piecing-roll 14; and an upper detach-

ing roll 15. The roll 15 usually is covered with leather or other suitable fabric 15^a on a larger part across the machine, and has a reduced journal portion 15^b at each end on 5 which is an annular flange 15^c between which and an abutment 15^d at the end of the larger fabric-bearing part the end of a stirrup 16 rests, the flange and abutment operating to prevent displacement of the stirrup longitudinally of the roll.

10 In machines of the class referred to, having rolls arranged substantially as described, fouling matter accumulates on the roll 15 between the end of its fabric covering, which 15 usually does not extend entirely up to the termination of the larger portion of the roll at abutment 15^d, and that abutment, and thence at times it works toward the end of the roll and into the bearings. There also is 20 a tendency of fouling matter to accumulate in the space between the three rolls at A, Fig. 6. For the purpose of preventing these accumulations of fouling matter and its subsequently being drawn into the output of the 25 machine, the device is associated with the rolls as shown. That is, the holding part 8 of the device is placed on roll 15 between its flange 15^c and abutment 15^d; and then the end of stirrup 16, instead of resting directly 30 on the roll, rests on the part 8 and against the then upper part 12, which latter operates to prevent displacement of the stirrup. The stirrup in turn operates to hold the device in place. The covering 10 on the concave side of the lower part 9 is held under 35 the rotative influence of roll 15 and in a measure by the stirrup against the lower roll 13. The lower part 9 being wider than the intermediate or holding part, it extends 40 laterally, and its covering, and particularly the flap 11 thereof, contacts with that part of the larger portion of roll 15 at the end that is devoid of fabric covering. Thus it will be seen that the gaps between and on 45 the rolls are filled in by the device and accumulations in those places prevented. It will be understood, of course, that a similar device is associated in like manner with the rolls at their other ends.

50 Having thus described my invention, what I claim as new, and desire to secure by Letters Patent, is—

1. A device of the class described, comprising a curved part adapted to contact 55 with and to be supported by a roll, and continuing therefrom a wider reversely-curved part adapted to contact with an adjacent roll.

60 2. A device of the class described, comprising a curved part adapted to contact with a roll, continuing therefrom a reversely-curved part having a portion extending laterally beyond the first-mentioned 65 curved part, and a fabric covering on said reversely-curved part and extending there-

from whereby a flap is formed and said covering being arranged on the concave side to contact with an adjacent roll and said flap to contact with the roll upon which said first-mentioned curved part rests. 70

3. In a machine of the class described, the combination, with adjacent coöperating rolls, of a device comprising a curved part in contact with and supported by one roll and continuing therefrom a reversely-curved 75 part in contact with an adjacent roll, whereby the gap between said rolls is spanned.

4. In a machine of the class described, the combination, with coöperating rolls, of a device comprising a part partially embracing 80 and supported by one roll and continuing therefrom a reversely-curved part extending to and in contact with an adjacent roll.

5. In a machine of the class described, the combination, with an upper detaching-roll 85 having a fabric covering and a lower piecing-roll, of a device comprising a curved part on said upper roll and continuing therefrom a reversely-curved part in contact with said lower roll and having a laterally-disposed portion extending toward the end of 90 the covering of said upper roll.

6. In a machine of the class described, the combination, with an upper detaching-roll 95 having a fabric covering and a lower piecing-roll, of a device comprising a curved part on said upper roll, continuing therefrom a reversely-curved part, a fabric covering on said latter part adapted to contact with said lower roll and having a flap in 100 contact with said upper roll adjacent to the end of its fabric covering.

7. In a machine of the class described, the combination, with an upper detaching-roll 105 having a fabric covering and a lower piecing-roll, of a device comprising a curved part on said upper roll, continuing therefrom a reversely-curved part in contact with said lower roll and having a laterally-disposed portion extending toward the end of 110 the covering of said upper roll, and a covering of sheet material on said reversely-curved part having a flap in contact with said upper roll adjacent to the end of its fabric covering. 115

8. In a machine of the class described, the combination, with coöperating rolls and a stirrup imposed on one of the rolls, of a device comprising a curved part interposed between the stirrup and the roll upon which it 120 is imposed, and continuing therefrom a reversely-curved part in contact with the other roll.

9. In a machine of the class described, the combination, with coöperating rolls and a stirrup imposed on one of the rolls, of a device comprising a holding part interposed between the stirrup and the roll upon which it is imposed, extending from the holding part in one direction an end portion in con- 125 130

tact with the other roll, and extending from the holding part in a diverse direction an end portion in contact with said stirrup.

10. In a machine of the class described, 5 the combination, with an upper detaching-roll having a fabric covering and a lower piecing roll and a stirrup imposed on the upper roll, of a device comprising a curved part interposed between the stirrup and 10 upper roll, continuing therefrom a reversely-curved part in contact with said lower roll and having a laterally-disposed portion ex-

tending toward the end of the covering of said upper roll, and a covering of sheet material on said reversely-curved part having a 15 flap in contact with said upper roll adjacent to the end of the fabric covering thereof.

In testimony whereof I affix my signature in presence of two witnesses.

JOSEPH MIDGLEY.
